FIG. 4.

Gus D. Stevens.

By B. P. Johnson

Attorneys

UNITED STATES PATENT OFFICE

2,256,955

SWING

Gus D. Stevens, Norcross, Ga.

Application October 18, 1940, Serial No. 361,787

4 Claims. (Cl. 155—65)

My invention relates to swings.

An important object of the invention is to provide a swing which may be used and operated by an adult or child and which is safe in operation.

A further object of the invention is to provide a swing which may be occupied by the user without the necessity of straddling parts thereof.

A further object of the invention is to provide a swing which is extremely simple in construction and cheap to manufacture.

A further object of the invention is to provide a swing which is propelled by the operator by effecting a relative angular movement between the seat and hand grip.

A further object of the invention is to provide a swing which is adjustable within limits for accommodating users of different sizes.

Other objects and advantages of the invention will be apparent during the course of the following description.

In the accompanying drawing forming a part of this application and in which like numerals are employed to designate like parts throughout the same,

Figure 1 is a perspective view of a swing embodying my invention,

Figure 2 is a front elevation of the same,

Figure 3 is a detailed section on line 3—3 of Figure 1,

Figure 4 is a detailed section on line 4—4 of Figure 1,

Figure 5 is a detailed section taken on line 5—5 of Figure 2, and,

Figure 6 is a similar view taken on line 6—6 of Figure 2.

In the drawing, wherein for the purpose of illustration is shown a preferred embodiment of my invention, the numeral 5 designates a generally U-shaped horizontal frame, having its forward side open. This U-shaped frame includes sides 6 and a rear end 7. The U-shaped frame is preferably rigid and is preferably formed of pipes or tubing. At their forward ends, the sides 6 have couplings 8 secured thereto and these couplings are provided with pairs of spaced knuckles 9, receiving therebetween coacting knuckles 10. The knuckles 9 and 10 are pivotally connected by a pin or bolt 12, as shown. The knuckles 10 have sleeves 13, preferably formed integral therewith.

The numeral 14 designates a preferably rectangular forward frame which is generally vertical in use. This frame comprises sides 15, a top 16, and a bottom 17, all of which are rigidly connected. The frame 14 is preferably rigid and is preferably formed of pipes or tubing. The

sleeves 13 are vertically disposed and are mounted upon the sides 15, and are vertically adjustable thereon and are clamped in the selected adjusted position by means of set screws 18. It is thus apparent that the generally horizontal U-shaped frame 5 is pivotally connected with the generally vertical frame 14, at points between the upper and lower ends of the vertical frame.

The numeral 19 designates a seat as a whole 10 for receiving one or more operators or users and this seat comprises a bottom 20 formed of slats 21 which are attached to the horizontal portions of straps 22. These straps are rigidly mounted upon horizontal transverse supporting elements 23, which may be rods, pipes, or the like. The seat comprises a back formed of slats 24, attached to the upstanding portions of the straps 22. The rods 23 are secured to T-couplings 25 including sleeves 26, which are mounted upon the sides 6 and are adjustable longitudinally thereof and the sleeves 26 may be clamped to the sides 6 in the selected adjusted position by set screws 27. By the vertical adjustment of the sleeves 13, the vertical distance between the seat and the lower end or foot rest 17 may be varied and the horizontal distance between the seat and the foot rest 17 may be varied by adjusting the sleeves 26 upon the sides 6.

The forward frame 14 is supported by flexible elements, cables, or wires 28, having loops 29 enclosing thimbles 30, which receive the top or hand grip 16. The rear end of the frame 5 is supported by flexible elements, cables, or wires 31, having loops 32 enclosing thimbles 33, receiving the end 7.

In use, the sleeves 13 and 26 will be set at the selected adjusted positions to regulate the distance between the seat and the foot rest 17. The user enters the swing at the forward 40 end thereof through the open frame 14 and becomes seated upon the seat 19. The user holds the top or hand grip 16 in the hands while the feet are placed upon the bottom or foot rest 17. The swing is supported by the cables so that the foot rest 17 suitably clears the ground and the user propels the swing by turning the frame 5 upon the pivots 12 with respect to the seat, as is obvious.

While I contemplate having the seat adjustable 50 with respect to the foot rest 17, this adjustability will be within limits and I contemplate constructing the swing in different sizes as may be required to meet the convenience of the users.

It is to be understood that the form of my invention herewith shown and described is to be

taken as a preferred example of the same and that various changes in the shape, size, and arrangement of parts may be resorted to without departing from the spirit of my invention or the scope of the subjoined claims.

Having thus described my invention, what I claim is:

1. A swing comprising a generally horizontal generally U-shaped frame open at its forward end so that the user may enter the frame through the forward open end, a seat separate from said frame and including a bottom and a back, the bottom being mounted upon the generally horizontal frame and the seat facing toward the forward open end of the frame, a generally vertical frame disposed adjacent to the forward open end of the generally U-shaped frame and pivotally connected therewith and extending above and below the same, the upper portion of the frame serving as a hand grip and the lower portion as a foot rest, flexible means for suspending the generally vertical frame, and flexible means for suspending the generally U-shaped frame.

2. A swing comprising a generally horizontal generally U-shaped frame open at its forward end so that the user may enter the frame through its forward end, a seat separate from the frame mounted upon the frame and facing toward its open end, said seat being spaced from the rear closed end of said frame, generally vertical sides pivotally connected with the sides of the generally U-shaped frame adjacent to its forward open end and extending above and below the generally U-shaped frame, a foot rest connecting the lower ends of said generally vertical sides, a hand grip connecting the upper ends of said generally vertical sides, flexible means suspending the generally vertical sides, and flexible means suspend-

ing the generally U-shaped frame and arranged near its closed end.

3. A swing comprising a generally horizontal generally U-shaped frame having sides and an end, the forward end of the frame being open so that the user may enter the frame through the forward open end, a generally vertical generally rectangular frame disposed adjacent to the ends of said sides at the forward open end of the generally U-shaped frame and pivotally connected with said sides and extending above and below the same, the top of the generally vertical frame forming a hand grip and its bottom forming a foot rest, transverse supporting means mounted upon the sides of the generally horizontal generally U-shaped frame, a seat mounted upon said transverse supporting means, flexible suspension means secured to the top of the generally vertical frame, and flexible suspension means secured to the end of the generally U-shaped frame.

4. A swing comprising a generally horizontal generally U-shaped frame having sides and an end, the frame being open at its forward end so that the user may enter such frame through its forward end, a generally vertical frame having sides and a top and bottom, the top serving as a hand grip and the bottom as a foot rest, couplings secured to the ends of the sides of the generally U-shaped frame and vertically adjustably mounted upon the generally vertical frame, a support, adjustable means for mounting the support upon the sides of the generally U-shaped frame so that the support may be shifted longitudinally thereof, a seat mounted upon the support, suspension means for the generally vertical frame, and suspension means for the generally U-shaped frame.
